UNITED STATES PATENT OFFICE.

FORREST EUGENE RICKETTS, OF BALTIMORE, MARYLAND.

ELECTRIC REGULATOR.

1,146,954.

Specification of Letters Patent. Patented July 20, 1915.

Application filed September 20, 1910. Serial No. 582,957.

To all whom it may concern:

Be it known that I, FORREST E. RICKETTS, a citizen of the United States, residing in Baltimore and State of Maryland, have invented a new and useful Electric Regulator, of which the following is a specification.

This invention has reference to improvements in electric regulators, and its object is to provide a regulator which will maintain the characteristic to be regulated sensibly constant.

The present invention relates to that class of regulators wherein contacts are moved into and out of engagement and the duration of the engagement of the contacts, or the time during which they are disengaged is varied by changes in the characteristic of the current to be regulated. It has been proposed to control such contacts by the electrical conditions of the system being regulated, but in practice such controlling means is found defective in that the slow response of the controlling means for the contacts gives time for such building up of the characteristic to be regulated as to cause it to surpass the desired limit, and also the drop of the characteristic becomes too great, until finally there may be established a surge far beyond the limits of close regulation.

By the present invention but one of the contacts is responsive to the electrical conditions of the system, while the other contact is kept in constant motion to and from the first contact to make and break electrical connection therewith at frequent intervals, the periodicity of movement of the continuously movable contact being such that at no time can the building up or drop of the current characteristic being regulated pass beyond that necessary to bring the system to the normal or mean condition.

By causing a continual movement to and from engaging position of one of the contacts by means independent of the electrical conditions of the system the periodicity of the make and break of the circuit at the contacts may be adjusted at will and to any desired degree in accordance with the demand, whereby there is obtained a closeness of regulation not possible in regulators where the approach and recession of the contacts is due solely to the electrical side of the system.

The invention will be best understood from a consideration of the following de-

tailed description taken in connection with the accompanying drawings forming a part of this specification, with the understanding, however, that the showing of the drawings being diagrammatic does not confine the invention to any special apparatus, nor is it necessary that the practical embodiment of the invention shall follow the exact arrangement shown in the drawings, the invention being susceptible of various modifications without material departure from the spirit and scope of the invention.

In the drawings:—Figure 1 is a diagram showing an alternating current system and a direct current system connected through a rotary converter with the controlling means of the present invention incorporated therein. Fig. 2 is a diagram illustrating the application of the present invention to an alternating current generator. Fig. 3 is a perspective view of a contact actuating means which may be employed in connection with the present invention. Fig. 4 is a diagrammatic representation of another contact actuating means which may be used in connection with the present invention.

Referring to the drawings, and first to Fig. 1, there is shown a rotary converter 1 having alternating current mains 2, 3, respectively, and direct current mains 4, 5, respectively. The mains 2, 3 are connected to the terminals of the low voltage side of a transformer 6, and included in series in one of the mains, say the main 2, is a reactance coil 7, and in series in the other main, say the main 3, there is included one coil of a current transformer 8, the other coil of which is connected to conductors 9, 10. The transformer 8 is so designed that the current supplied to the conductors 9 and 10 will bear a definite ratio to the current flowing in the main 3. One terminal of the high voltage side of the transformer 6 is connected to a conductor 11, and the other terminal of this transformer is connected through a switch 12 to a conductor 13, the conductors 11 and 13 constituting the incoming power conductors. The switch 12 is only diagrammatically represented and is designed to change the ratio of the transformer 6 by cutting in or out a portion of the winding, one arm of the switch having in its path suitable terminals 12^a properly connected to the high voltage side of the transformer 6. The switch 12 is operated by two cores 14, 15 controlled by solenoids 16, 17, respec-

tively, the construction being such that when one solenoid is energized the switch will be rocked to move over the contacts 12^a in one direction, and when the solenoid 17 is energized the switch will move over the contacts 12^a in the other direction. One terminal of the coil 16 is connected to one terminal of the coil 17 by a conductor 18. The other terminal of the coil 16 is connected by a conductor 19 to a contact 20, and the other terminal of the coil 17 is connected by a conductor 21 to a contact 22, the two contacts 20 and 22 being adjacent but spaced apart an appropriate distance. The conductor 18 is connected by a conductor 23 to another conductor 24, which in turn is connected to the main 2.

There is provided a disk 25 of non-magnetic metal provided with a shaft 26 which may be mounted so that the disk is free to turn, so far as its mounting is concerned, in said mounting about the longitudinal axis of the shaft 26. The disk is provided on one side with an arm terminating in a contact 27 movable into engagement with either of the contacts 20 or 22, but the contact 27 is normally centralized between the contacts 20 and 22 by springs 28, 29, respectively, attached to opposite sides of the arm carrying the contact 27, and one or other of these springs must be extended or compressed as the case may be in order that the contact 27 may be brought into engagement with one or other of the contacts 20 and 22. The contact 27 is connected by a conductor 30 to another conductor 31 leading to the main 3.

The disk 25 is suspended in the field of a horseshoe electro-magnet 32 having both of its poles near one face of the disk, and substantially equi-distant from the center thereof. In operative relation to the other face of the disk and equi-distant from the poles of the magnet 32, is the pole of another magnet 33, which is an electro-magnet of the bar type. The magnet 32 is wound with coils 34, 35 connected together in series, and having their terminals connected, respectively, to the conductors 9 and 10. The magnet 33 is wound with a coil 35 which is bridged across the mains 2 and 3 by respective conductors 36, 37, and included in one of the conductors, say the conductor 37 is a resistance 38 designed to maintain the current in the coil 35 approximately in phase with the voltage of the mains 2 and 3. The purpose of the structures and circuits so far described will appear hereinafter.

The rotary converter 1 is provided with a field coil 39 having one terminal connected by a conductor 40 with the main 5, and the other terminal connected by a conductor 41 to one side of a rheostat 42 of the adjustable type and in series with the field 39. The other terminal of the rheostat 42 is connected to a conductor 43 leading from the main

4 to one terminal of a small generator 44, the other side of which is connected in series with a similar generator 45 by a conductor 46, while the other side of the generator 45 is connected by a conductor 45^a to the conductor 40. The conductor 46 is connected by a conductor 47 to the conductor 41. The generator 44 is, therefore, in parallel with the resistance 42 and the generator 45 is in parallel with the field coil 39. The generators 44 and 45 are mounted on a common shaft 48 driven by a motor 49 of any suitable type, and which may be taken as indicative of any suitable means for applying power to the shaft 48.

The generator 44 has a field coil 50 and the generator 45 has a field coil 51, which field coils are connected together in series by a conductor 52. These two field coils in series are bridged across the mains 4 and 5 by conductors 53 and 54. A movable member 55 constituting a switch arm is connected to the conductor 52 and is capable of moving about an axis which may be coincident with its connection with the conductor 52. This movable member or arm 55 has in its path a contact 56 and is normally constrained away from its contact by a spring 57 and may be moved against the action of the spring by a magnet 58. The movement of the arm 55 under the action of the spring 57 is limited by a contact 59. An adjustable rheostat 60 is connected on one side of the contact 56 and on the other side by a conductor 61 to the conductor 53, and a rheostat 62 is connected on one side to the contact 59 and on the other side to the conductor 54. One terminal of the coil of the magnet 58 is connected to the conductor 24, while the other side of the magnet 58 is connected by a conductor 63 to a switch lever 64 having at one end a flexible extension 65 which may be in the form of an elastic metallic strip, and this extension 65 carries at its outer end a contact 66, in the path of which is another contact 67 on the free end of an elastic strip or arm 68, which may be appropriately secured at the other end to a fixed member 69, and there also connected to the conductor 31. The elastic strip 68 carries a block 70 in the path of a cam 71 on one end of a shaft 72 which may be driven by a motor 73 simply indicated in the drawings, but which may be considered as any suitable type of motor capable of running at a substantially constant speed when properly set, but it will be understood that the speed of this motor may be varied by any appropriate means to any desired degree. The shaft 72 also carries a disk 74 of non-magnetic metal rotatable in the field of a permanent magnet 75 mounted on an adjustable support 75^a, so that the magnet may be made to embrace more or less of the disk to thereby vary the speed of 130

the shaft 72 and the eccentric 71 carried thereby.

The lever 64 on the side of its pivot support remote from the extension 65 is coupled to a core 76 movable in one direction by gravity, and the movement of which is retarded by a dash pot 77, which latter may be provided with an adjustable by-pass 77^a. The core 76 is movable in a coil 78, one side of which is connected by a conductor 79 to one of the direct current mains, say the main 5, and the other side of which is connected by a conductor 80 to the other current main, say the main 4, so that this coil is energized by the voltage of the mains 4 and 5. The core 76 is also under the control of another coil 81, one terminal of which is connected by a conductor 82 to one of the direct current mains, say the main 5, while the other side of this coil is connected to another conductor 83 to the same main 5, and between the point of connection of these conductors 82 and 83 with the main 5 there is introduced a resistance 84, this resistance being in series in the said main. The coil 81 is therefore in parallel with the resistance 84 and is energized by the current of the mains 4 and 5. The magnetism of the magnet made up of the core 76 and coils 78 and 81 is, therefore, the resultant of the current and voltage of the mains 4 and 5.

The apparatus indicated in Fig. 1 operates to maintain a constant voltage of the mains 4 and 5, and at the same time holds the current and voltage of the mains 2 and 3 in phase.

Let it be assumed that the motor 73 is running at a practically constant speed, and, therefore, the action of the cam 71 on the elastic strip or contact arm 68 is to cause the latter to move up and down through a slight distance at each revolution of the cam, the parts being properly proportioned for this purpose. Let it also be assumed that the voltage of the mains 4 and 5 has increased sufficiently to carry the contact 66 out of engagement with the contact 67 by the energization of the coil 78 to an extent sufficient to raise the core 76 to the proper degree for this purpose. The movement of the contact 66 out of engagement with the contact 67 will interrupt the current flowing in the magnet 58, since the circuit including the contacts 66 and 67 is from the main 3 through the conductor 31 to the arm 68, thence by way of the contacts 67 and 66 to the extension 65 and lever 64 to the conductor 63, thence through the coil of the magnet 58, returning to the main 2 by way of the conductor 24. While the magnet 58 is in the energized condition, the lever 55 has been pulled toward its magnet against the action of the spring 57, and the lever has been brought into engagement with the contact 56. Now, however, the deenergization

of the magnet 58 has allowed the spring 57 to pull the arm 55 into engagement with the contact 59 and consequently all the current flowing from the conductor 53 must pass through the field coil 50, thus raising the voltage of the generator 44 and therefore the voltage across the resistance 42 by sending more current therethrough, but the current passing through the field coil 50 will divide between the resistance 62 and the field coil 51, which will weaken the strength of the field 51, so that the voltage of the generator 45 will decrease, and the generator 45 will, therefore, supply less current to the field coil 39. In this way the strength of the field 39 is weakened first by increasing the voltage drop across the resistance in series with it, and second, by decreasing the voltage drop across itself. This weakening of the field 39 decreases the voltage of the mains 4 and 5 by causing the current in the mains 2 and 3 to lag behind the voltage. This drop in voltage will be increased by the reactance 7. As soon as the current in the mains 2 and 3 lags behind the voltage, the magnetism of magnet 32 will lag behind that of magnet 33 and this produces a rotating field in the non-magnetic disk 25, causing it to rotate in a direction to bring the contact 27 into engagement with the contact 20, thus establishing a circuit from the main 2 by way of the conductors 24 and 23 to the conductor 18, thence through the coil 16 by the conductor 19 to the contact 20, returning to the main 3 by way of the contact 27 and conductors 30 and 31. This causes a movement of the switch 12 in a direction to cut in some of the turns of the coil of the transformer 6 connected to the mains 11 and 13, and this will decrease the voltage on the mains 2 and 3 and consequently the voltage of the mains 4 and 5. The decrease of voltage in the mains 4 and 5 causes a weakening of the coil 78 and the core 76 will, therefore, drop, turning the lever 64 on its pivot supports and bringing the contact 66 into engagement with the contact 67 during a portion of the cycle of movement of the latter. During the period of engagement of the contacts 66 and 67, the magnet 58 is energized, and the arm 55 is drawn against the action of the spring 57 away from the contact 59 and into engagement with the contact 56, thus depriving the field 50 of part of the current flowing from conductor 53 to conductor 54, such current flowing through the resistance 60 which is now in parallel with the field 50. The effect of this is to lower the voltage in the generator 44 and thus decrease the voltage drop across the resistance 42. Now, however, all of the current flowing through the resistance 60 and field coil 50 passes through the field coil 51, thus increasing the voltage of the generator 45, so that it takes less cur-

rent from the field coil 39, thereby allowing the voltage drop across the field coil 39 to increase. In this way the strength of the field 39 is increased, first by decreasing the voltage drop across the resistance in series with it, and, second, by increasing the voltage drop across itself. This increase of strength of the field 39 increases the voltage of the mains 4 and 5 by advancing the current in phase relation to the voltage of the mains 2 and 3.

The contact arm 55 will continue to vibrate between the contacts 56 and 59 engaging each contact once during each revolution of the eccentric 71, but the duration of time during which each contact is engaged will depend upon the time during which the contacts 66 and 67 are together, and this will depend upon the position which the core 76 occupies with relation to the coil 78, such position depending upon the voltage of the mains 4 and 5. When the voltage of these mains 4 and 5 is below the predetermined mean, the time of engagement of the contacts 66 and 67 is increased, causing the voltage of the mains 4 and 5 to rise, and when the voltage of these mains is above normal, the time of engagement of the contacts 66 and 67 will decrease, thus causing the voltage of the mains 4 and 5 to fall. In this way the voltage of the mains 4 and 5 is regulated by varying the phase relation of the current and voltage of the mains 2 and 3.

When the current on mains 4 and 5 increases, the voltage drop across the resistance 84 increases, which causes an increase of current on the coil 81. This opposes the magnetism of the coil 78, and a higher voltage on the mains 4 and 5 is then required to maintain a balance between the pull of the coil 78 and the weight of the core 76. The regulation will, therefore, operate to increase the voltage as the load increases.

When the current in mains 2 and 3 lags behind the voltage, a rotating field is set up in the disk 25 by the magnets 32 and 33, which field tends to rotate the disk to bring contact 27 into engagement with the contact 20, causing the switch 12 to cut in more turns of the primary of the transformer 6, which, as before explained, lowers the voltage of mains 2 and 3, and thereby of mains 4 and 5. This affects the contacts 66 and 67 to increase the field 39, thus causing the current to advance in phase relation to the voltage in the mains 2 and 3. When the current of mains 2 and 3 leads the voltage, the rotating field set up in the disk 25 by the magnets 32 and 33 causes this disk to bring the contact 27 into engagement with the contact 22, thus causing an operation of the switch 12 to cut out turns of the primary of the transformer 6 to raise the voltage of the mains 2 and 3 and thereby that of the mains 4 and 5. This affects the contacts 66 and 67

to decrease the current in the field coil 39, which delays the current in relation to the voltage in mains 2 and 3.

When the current in mains 2 and 3 is in phase with the voltage, the magnetism of the magnet 32 will be simultaneous with that of magnet 33 and consequently there is no force developed tending to rotate the disk 25.

Referring now to Fig. 2, there is shown an alternating current generator 85 with armature leads 86, 87 and field leads 88, 89, which latter are connected to the armature terminals of a small generator 90 constituting an exciter, which latter is provided with a field coil 91 and a resistance 92 in series across the armature leads of the exciter by conductors 93 and 94. There is provided an automatic switch comprising a switch arm 64^a with an extension 65^a and a contact 66^a at its free end like the similar members 64, 65 and 66 of Fig. 1. That end of the lever 64^a remote from the contact 66^a is connected to a core 76^a like the core 76 of Fig. 1, and this core is under the control of two coils 78^a and 81^a, as in Fig. 1, and is also provided with a dash pot 77 as in Fig. 1. In Fig. 2 the contact arm 68 is replaced by a bell crank lever 95 having at the end of one arm a contact 96 in the path of the contact 66^a. The other end of this lever is extended in the form of a substantially pendent rod 97 carrying an adjustable weight 98 and this rod 97 is engaged by one end of another rod 99 fast to an anchor escapement 100 controlling an escapement wheel 101 like the controlling escapement of an ordinary clock. The escapement wheel 101 is assumed to be driven by a motor symbolized by the wheel 102 driving the escapement wheel 101. Any type of motor capable of running at any desired speed with substantial constancy for suitable periods of time will answer. The rod 97 with its weight 98 is in effect a pendulum, the speed of which is controllable by the weight 98 adjustable along the rod 97. The contact lever 64^a is connected to one side of the resistance 92 by a conductor 103 and the lever 95 is connected to the other side of the resistance 92 by a conductor 104, this last named conductor connecting to the lever 95 preferably at the pivot point thereof as indicated at 105. The coil 78^a is bridged across the terminals of the secondary coil of a voltage transformer 106 by means of conductors 107, 108, and one of these conductors, say the conductor 108 includes a resistance 109, the object of which is to keep the current in coil 78^a approximately in phase with the voltage of the transformer 106. This is made necessary by the fact that the current in this circuit is of an alternating character, and would, therefore, lag behind the voltage if the circuit did not contain an ohmic component. The primary coil of the transformer 106 is bridged across the mains 86, 130

87, so that the current applied to the coil 78^a is in proportion to the voltage of said mains. The coil 81^a is wound to oppose the magnetism of coil 78^a and is connected to the secondary winding of a transformer 110 by conductors 111, 112. The primary coil of the transformer 110 is in series with one of the mains 86, 87, say the main 87, and furnishes to the coil 81^a a current always in proportion to the current flowing in the main 87. Therefore, the magnetism acting on the core 76^a will be the resultant of that of the coils 71^a and 81^a. The dash pot 77 performs the same function as the one similarly arranged in Fig. 1.

When the regulator shown in Fig. 2 is in operation, the contact 96 is kept in motion by the swinging of the pendulum lever 95 driven by the motor 102 through the escapement 100, 101. When the voltage in the mains 86, 87 rises above a predetermined mean the voltage supplied by the transformer 106 to the coils 78^a will increase, causing the contact 66^a to engage the contact 96 for a shorter period of time during each cycle of the contact 96, the energization of the coil 78^a being such as to draw the core 76^a into it to a further extent than formerly, thus moving the contact 66^a in a direction away from the contact 96 to a commensurate extent. When the contacts 66^a and 96 are in engagement, the resistance 92 is short circuited, and the voltage of the exciter 90 is thereby increased with a like increase of the voltage of the generator and of the mains 86 and 87. Because of the shortened time of engagement of the contacts 66^a and 96 under the conditions just assumed, the voltage on the mains 86 and 87 will be lowered, and then said contacts will again engage for a sufficient time during each cycle of the contact 96 to maintain a balance between the pull of the coil 78^a and the weight of the core 76^a. If the voltage of the mains 86 and 87 decreases, the weight of the core 76^a will overbalance the pull of the coil 78^a which has been correspondingly weakened by the decrease of voltage of the mains 86 and 87, so that the contacts 66^a and 96 will remain in engagement for a longer time to cause a rise in voltage of the exciter, and by such rise, a rise in voltage of the generator. When the load on the mains 86 and 87 increases, the current supplied by the transformer 110 to the coil 81^a will increase, and because of the relation of the coil 81^a to the coil 78^a, will tend to demagnetize the said coil 78^a, so that a higher voltage on the mains 86 and 87 is required to establish a balance between the pull of the coil 78^a and the weight of the core 76^a. Therefore, the regulator will operate to increase the voltage as the load increases, and this is equally true of the same structures of Fig. 1.

Fig. 3 is a slightly modified form of the

contact structure of Fig. 1, wherein current is supplied directly to the shaft 72 by a brush 113 connected to the conductor 31 and the eccentric 71, which is made of conducting material and is electrically connected to the shaft 72, and contacts periodically with the contact terminal 66 on the end of the extension 65 of the lever 64, thus establishing the circuit between the conductors 31 and 63 periodically at a frequency depending upon the speed of rotation of the shaft 72 and for a time duration at each contact depending upon the position of the lever 64 under the action of the coils 78 and 81.

In Fig. 4 there is shown another type of motor for imparting movement to the vibratory contact. The spring arm 68 is traversed by a rod 114 to which the spring arm is secured. On one side of the arm 68 the rod 114 is connected to one end of a spring 115, the other end of which may be connected to any suitable fixed support. The other end of the rod 114 carries a core 116 entering a coil 117, one terminal of which latter is connected by a conductor 118 to one side of a battery 119 which may be taken as indicative of any suitable source of electrical energy, and the other side of the battery 119 is connected by a conductor 120 to a contact terminal 121. The other side of the coil 117 is connected to a contact terminal 122 carried by a finger 123 on the core 116, and this finger may be elastic. The core 116 is also controlled by a dash pot 124 provided with a by-pass 125, whereby the effect of the dash pot may be regulated. The tendency of the spring 115 is to maintain the contacts 66 and 67 separated, and also to move the contact 122 into engagement with the contact 121. As soon as the contacts 121 and 122 are brought into engagement, current from the battery 119 energizes the coil 117 and the core 116 is drawn into the coil 117 in a direction to expand the spring 115 and bring the contact 67 into engagement with the contact 66, oscillations of the core 116 and arm 68 being deadened by the dash pot 124. By having a spring finger 123 carrying the contact 122, the engagement of the contacts 121 and 122 is sufficiently prolonged to give the desired extent of travel of the contact 67. The periodicity of vibration of the contact 67 may be readily determined or changed by proper proportioning of the spring 115 and the relation of the contacts 121 and 122. In the structure shown in Fig. 4, the arm 68 may or may not be elastic, and if non-elastic may be pivoted at the end remote from the contact 67, as indicated at 126 in Fig. 4.

It is desirable that the core 76 of Figs. 1, 3 and 4 or 76^a of Fig. 2 should maintain a position relative to the controlling coil or coils due solely to the magnetic conditions established in these coils, and this core 130

should change its position only in accordance with changes in such magnetic conditions. No sensible changes in the position of the core should occur under the action of the constantly moving contact. For this reason one or both of the contacts 66 and 67 of Figs. 1 and 4, or 66^a and 96 of Fig. 2 or 66 and 71 of Fig. 3, should be elastically mounted. The constantly movable and positively driven contact has a certain predetermined range of movement considering the other contact as not present. The matching contact is positioned with relation to the constantly movable contact to be engaged thereby during a portion of the travel of the constantly movable contact, the time duration of engagement depending upon the position of the contact controlled by the electrical conditions of the circuit. Since the contact controlled by the circuit to be regulated must not sensibly change its position except in response to changes in the electrical conditions of the circuit, but still respond promptly to such changes, the dash pot control is provided. The changes in the electrical conditions of the circuit are not so rapid but that the dash pot will permit the response of the contact controlled thereby to such changes in the electrical conditions, while said dash pot is practically unresponsive to the comparatively rapid movements of the positively and constantly moved contact. The elastic mounting of one of both contacts compensates for the differences between the movement of the two contacts, and, also, provides for the longer or shorter period of engagement of the contacts.

No definite speed of movement of the constantly actuated contact can be given, since the speed of movement may be varied within quite wide limits. It has been found, however, that good results have been obtained when the speed of movement of the constantly actuated contact has been about two hundred cycles per minute. The rate of vibration of the constantly driven contact, considering this contact as a vibratory contact, may be much less than two hundred per minute, but the speed must be determined by the electrical conditions present in the circuit, one speed of vibration answering well for one circuit, and another speed of vibration for another circuit. When the circuit between the contacts is completed, the change of voltage due to the action of the regulator might reach the proportions of a surge if the comparatively slow responding electrical conditions were relied upon because the break of the circuit at these contacts, and then the reverse action might cause a drop in excess of the desired amount, and this is the actual occurrence in practice where the variations sometimes become excessive instead of the regulator hold-

ing the variations close to the desirable mean. With the present invention the time period of engagement of the contacts is determined by the constantly movable contact as modified by the electrical conditions of the circuit, but this time of contact never exceeds the period of the constantly movable contact, so that the characteristic being regulated cannot build up too high or fall too low, but is maintained very close to a theoretical constancy.

What is claimed is:—

1. The combination with an electrical circuit, and a dynamo-electric machine associated therewith, of a regulator comprising co-operating contact members, means for varying the position of one of said contact members in accordance with an electrical condition of only said circuit, and means for continuously vibrating said contact members into and out of engagement independently of the conditions of the aforesaid parts.

2. The combination with an electrical circuit, a dynamo-electric machine associated therewith and an exciter for the dynamo-electric machine, of a regulator comprising co-operating contact members, means for varying the position of one of said contact members in accordance with an electrical condition of the said circuit and independently of the condition of the exciter, and means for continuously vibrating said contact members into and out of engagement independently of the conditions of the aforesaid parts.

3. The combination with an electrical circuit, a dynamo-electric machine associated therewith, and an exciter for the dynamo-electric machine, of a regulator comprising co-operating contact members, one of which is resiliently mounted, means for varying the position of one of said contact members in accordance with an electrical condition of said circuit and independently of the condition of the exciter, and means for continuously vibrating said contact members into and out of engagement independently of the conditions of the aforesaid parts.

4. The combination with an electrical circuit, a dynamo-electric machine associated therewith, and an exciter for the dynamo-electric machine, of a regulator comprising co-operating contact members, one of which is resiliently mounted, means for varying the position of one of said contact members in accordance with an electrical condition of said circuit and independently of the condition of the exciter, and a cam for continuously vibrating said contact members into and out of engagement independently of the conditions of the aforesaid parts.

5. The combination with an electrical circuit, and a dynamo-electric machine associated therewith, of a regulator comprising

- coöperating contact members, one of which is resiliently mounted, means for varying the position of one of said contact members in accordance with an electrical condition of only said circuit, means for retarding movements of the latter contact member, and means for continuously vibrating said contact members into and out of engagement independently of the conditions of the afore-
5 said parts.
6. An electrical regulator comprising coöperating contact members, electrical means for actuating one of said contact members, and a continuously actuated cam for actu-
10 ating the other member.
7. An electrical regulator comprising coöperating contact members, one of which is resiliently mounted, electrical means for actuating one of said contact members, and a continuously actuated cam for actuating the other member.
15
8. An electrical regulator comprising coöperating contact members, and electrical means and a rotatable cam for separately causing relative movements of the contact members.
20
9. An electrical regulator comprising coöperating contact members, one of which is resiliently mounted, and electrical means and a continuously actuated rotatable cam for separately causing relative movements of the contact members.
25
10. An electrical regulator comprising coöperating contact members, a resilient supporting arm for one of said members, a cam for actuating said arm, a resilient mounting for the other member, and electrical means for actuating the latter member.
30
11. An electrical regulator comprising co-
35 operating contact members, resilient mount-
40
- ings for each of said members, a cam for actuating one of the contact members, and electrical means for actuating the other member.
12. An electrical regulator comprising two movable coöperating contact members, a rotatable cam for causing said members to engage and disengage, and means for rendering the movements of one of said members sluggish.
45
13. An electrical regulator comprising two movable coöperating contact members, a continuously rotating shaft, means for causing the contact members to engage and disengage at a rate proportional to the speed of rotation of the shaft, and means for rendering the movements of one of said members sluggish.
50
14. An electrical regulator comprising two movable coöperating contact members one of which is resiliently mounted, a continuously rotating shaft, means for causing the contact members to engage and disengage at a rate proportional to the speed of rotation of the shaft, and means for rendering the movements of one of said members sluggish.
55
15. An electrical regulator comprising coöperating contact members, and means for causing relative movements of the said members including a continuously-actuated cam and electrical means separate therefrom.
60
- In testimony, that I claim the foregoing as my own, I have hereto affixed my signature in the presence of two witnesses.
70
- FORREST EUGENE RICKETTS.
75
- Witnesses:
DOUGLASS C. GOSNELL,
JOHN T. FARBY.
